UNITED STATES PATENT OFFICE.

WINTHROP L. JACOBS, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,463, dated September 13, 1881.

Application filed August 9, 1881. Term of patent 3½ years.

To all whom it may concern:

Be it known that I, WINTHROP L. JACOBS, of East Orange, in the county of Essex and State of New Jersey, have invented a new and original Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

The ground of the carpet is divided into two parallel portions, A and B. The portion A has a lower stripe, a, and an upper stripe, b. Between these stripes are series of fanciful leaves, C D E F G, on a suitable background.

The stripe a is composed of vertically-placed narrow ornaments, and the stripe b by diagonally-placed blocks.

The part B of the carpet contains fanciful leaves H H, rosettes I, and an intermediate castellated stripe, J.

I claim—

1. The design for carpets, consisting of the figures A C D E F G, substantially as shown.
2. The design for carpets, consisting of the figures A C D E F G a b, substantially as shown.
3. The design for carpets, consisting of the figures B H I J, substantially as shown.
4. The design for carpets, consisting of the figures A C D E F G a b B H I J, substantially as shown.
